RADIO RECEIVER

Edward F. Andrews, Chicago, Ill.

Original application July 18, 1938, Serial No. 219,713, now Patent No. 2,262,218, dated November 11, 1941. Divided and this application February 3, 1941, Serial No. 377,096

7 Claims. (Cl. 250—20)

This invention relates to devices for tuning radio receivers in which tuning is effected by power means adapted to be set in operation by manually actuated means and adapted automatically to be rendered inoperative when the receiver has been tuned to the carrier wave of a broadcasting station received with sufficient strength, and is a division of my copending application Serial No. 219,713, filed July 18, 1938, which issued on November 11, 1941, as Patent No. 2,262,218. I call this general type of station selection "stop-on-carrier tuning." The manually actuated means comprises means controlling the change of an electric current or voltage and may be located at a point remote from the receiver. For example, it may be a manually actuated switch which is preferably located in remote relation to the receiver, being connected thereto by means of a cable.

The invention is very advantageous for tuning all varieties of radio receiver. It facilitates remote control and provides simple automatic tuning which does not require manual adjustments for setting up pre-selected stations.

The invention is very advantageous for effecting automatic tuning for automobile or other portable radio receivers where the receiver may be moved out of the vicinity of certain broadcasting stations and into the vicinity of others. As the form of automatic tuning of this invention will tune in the stations whose carrier waves are of sufficient strength to cause stoppage of the power means driving the tuning element, it is not necessary to re-set the device to tune in a new set of stations when the geographical location of the receiver is changed. The device automatically tunes in the stations broadcasting carrier waves of sufficient strength, regardless of what particular stations they may be, within the tuning range of the receiver.

As tuning from one station to another is effected merely by pressing a button, the tuning operation may be performed by the driver of an automobile without taking his eyes from the road. He may simply continue to operate the tuning button until he hears the desired station. This greatly enhances the safety of radio receiver operation by the driver of an automobile. As only a button or switch connected to the receiver by two small flexible wires is required for performing the tuning operation, this can be very conveniently mounted directly on the steering column, where the driver may operate it without taking his hand from the wheel, while the re-

ceiver may be mounted at any other suitable location in the automobile.

The invention is, of course, also adapted to the automatic tuning of stationary or home types of receivers, and also may be remotely operated in other ways. Also, many of the features described in connection with automobile sets are similarly advantageous for home receivers.

This invention relates particularly to means for securing the proper timing and for narrowing the electrical impulses which cause automatic stoppage on the carrier to effect more exact and uniform tuning. It relates, further, to an arrangement wherein the selectivity of a tuned circuit forming part of the receiving circuit is rendered sharp during tuning and broadened during reception to give a sound output of high fidelity and also to an arrangement utilizing the electron tubes and a tuned circuit normally utilized in the receiver, so that no additional tubes or separate tuned circuits are necessary to effect the desired control of the tuning means. Certain features of this invention are also applicable to receivers tuned manually.

The invention will be readily understood from the following description of an embodiment thereof taken in conjunction with the accompanying drawing, the single figure of which is a wiring diagram illustrating my invention and so much of a radio receiver as is necessary to understand the invention.

Referring now to the drawing, the tubes 10 and 11 are intermediate frequency tubes. The tube 12 is a second detector and first audio tube, 35 while the tube 13 is an audio frequency amplifier. As already indicated, the drawing is intended to illustrate only part of the radio receiver so in actual practice and as disclosed in my copending application, the tube 10 would be preceded by a radio frequency amplifying tube, and if the receiver is of the superheterodyne type, a first detector and oscillator tube and tuning condensers operable by power means, to be referred to hereinafter, for tuning the receiver to the carrier signals of radio stations. Likewise, the tube 13 would be connected to a loudspeaker in a manner well known to those skilled in the art.

The plate of tube 10 is connected to a primary 50 14 of a transformer 15. The tuned secondary 16 of this transformer is loosely coupled to the primary 14, and connected to the grid of tube 11 and to the leaf 17 of a multi-switch 18. The secondary 16 is also connected to an auxiliary winding 19, which is closely coupled to the pri-

mary 14. The winding 19 is connected to a leaf 20 of the multi-switch 18. The plate of the tube 11 is connected through a relatively closely coupled transformer 21 to the diode plates of the tube 12. The primary of transformer 21 is connected to a pole 22 of the multi-switch 18. The secondary of the transformer 21 is connected through a resistor 23 to the cathodes of the tube 12. The secondary of the transformer 21 and the resistor 23 are connected through a resistor 24 to a pole 25 of the multi-switch 18 and through a resistor 26 to the grid of the tube 10. The pole 27 of the multi-switch 18 is connected to the grid of tube 13. The leaf 28 of the multi-switch 18 is grounded. The pole 29 of the multi-switch 18 is connected through an automatic reversing switch 30 to a reversible motor 31 which is supplied with current from a transformer 32, which may be windings on the power transformer of the A. C. radio receiver. The motor 31 and switch 39 may be of the type described in my aforementioned copending application, that is, the motor is so constructed and arranged as to declutch itself from the tuning condensers when deenergized and to be clutched thereto when energized, and the reversing switch 30 is actuated from one of its two positions to the other by limit switch mechanism operated at the limits of movement of the condensers.

The leaf 33 of the multi-switch 18 is grounded, the leaf 34 is connected to the B supply, and the leaf 35 is connected through a winding 36 of a relay 37 to the B supply. The leaf 35 is also connected through a resistor 38 and a normally open, manually operable switch 39 to ground.

The poles 25, 27, 29 and 22 are mechanically connected to the armature 40 of the relay 37. When the relay is deenergized, the armature 40 is moved away from the relay by a spring 41, with the result that the pole 25 is in contact with the leaf 20 and is separated from the leaf 17, the pole 27 is separated from the leaf 28, the pole 29 is separated from the leaf 33, and the pole 22 is in contact with the leaf 34 and is separated from the leaf 35. When the relay 37 is energized, it attracts the armature 40, with the result that the pole 25 is separated from the leaf 20 and is in engagement with the leaf 17, the pole 27 is in engagement with the leaf 28, the pole 29 is in engagement with the leaf 33, and the pole 22 is separated from the leaf 34 and is in engagement with the leaf 35. The leaves 20 and 17 are biased so that they follow the pole 25 when it moves from one position to the other so as to insure the engagement of the pole with the second leaf before it separates from the first leaf. The leaves 34 and 35 are similarly biased towards the pole 22. Consequently, one of the leaves 17 and 20 is in contact with the pole 25 at all times, and one or other of the leaves 34 and 35 is in contact with the pole 22 at all times.

The operation is as follows: When energy is supplied to the set, if the same is tuned to a station, that station will be received. If the switch 39 is closed, the relay 37 is energized by "B" current flowing through the winding 36, the resistor 38 and the switch 39. Consequently, the pole 29 is brought into engagement with leaf 33, and the motor operates and remains in operation so long as the switch 39 is held closed. When the relay 37 is thus energized, the pole 27 is in engagement with the leaf 28, and the grid of the tube 13 is grounded so that the set remains mute. If the switch 39 is now allowed to open, or if it had been merely depressed momentarily, the relay 37 re-

mains energized and the motor continues to operate until a station of adequate strength is tuned in, owing to the movement of the gang of condensers. While the motor is operating after the switch 39 is opened, the relay 37 is energized by the flow of "B" current through the winding 36, leaf 35, pole 22 and the plate of tube 11. Owing to the fact that no station is being received, there is little voltage drop across the resistor 23. Consequently, the plate current of the tube 11 is quite high. When, however, a signal of sufficient strength is received, a voltage drop is applied across the resistor 23 so that the negative bias of the grid of the tube 11 is strongly increased and the plate current of the tube 11 is strongly decreased so that the relay 37 opens.

It may here be noted that when a station is tuned in and the relay 37 is deenergized, the grid circuit includes the windings 16 and 19 in series. Since the winding 19 is closely coupled to the winding 14, the transformer 15 is more broadly tuned so as to provide for the passage of a signal of desired characteristics for audible reproduction. When, however, the motor is operating, the winding 19 is cut out by the separation of pole 25 from the leaf 20, and, consequently, the effective coils of the transformer 15 are the primary 14 and secondary 16. These windings are loosely coupled so that the selectivity of the circuits is considerably increased. In other words, the form of the resonance curve for each station is rendered more narrow and more accurate tuning is thereby obtained for stop-on-carrier operation. When the relay 37 is deenergized in response to the reception of a carrier signal, the closely coupled winding 19 is again introduced into the grid circuit of the tube 11.

It will be noted that the double throw switch, which includes the pole 22 and the leaves 34 and 35, provides a locking system which prevents the operation of the motor in the event that the station received fades, or indeed goes off the air. The only manner in which the motor may be again put into operation is by the closing of the switch 39. It will, however, be understood that a locking effect may be obtained by providing the armature 40 with sufficient movement away from the relay 37 so that it cannot be attracted by any energization of the relay 37 other than the strong energization provided by the closing of the switch 39. This requires the throw of the armature 40 to be sufficient to move it from one position, in which it is strongly attracted by the flux, into a remote position, where the flux is relatively weak. When the relay is locked out in this manner, the pole 22 and leaves 34 and 35 may be omitted and the conductors connected to the pole 22 and the leaf 35 may be merely connected together. This modification connects the relay winding 36 and the resistor 38 directly to the plate circuit of the tube 21.

Although the invention has been described in connection with the specific details of a preferred embodiment thereof, it must be understood that such details are not intended to be limitative of the invention except in so far as set forth in the accompanying claims.

Having thus described my invention, I declare that what I intend to claim is:

1. In a radio receiver having a tuned circuit with a broad selectivity curve, at least one grid controlled radio frequency amplifying tube and a power actuated means for operating tuning means, in combination, means including a device responsive to the plate current of said tube for

stopping said tuning means when a carrier signal is closely tuned in, and means including a circuit controlled in response to the plate current of said tube for increasing the selectivity of said tuned circuit during operation of said tuning means.

2. In a radio receiver having a tuned circuit having a broad selectivity curve and variable tuning means, in combination, power means for operating said tuning means, an electron tube having a control grid energized from said tuned circuit and a plate, means associated with said tuned circuit for increasing its selectivity, and means responsive to the plate current of said tube for substantially simultaneously rendering said power means effective to operate said tuning means and said selectivity increasing means to increase the selectivity of said tuned circuit.

3. In a radio receiver having variable tuning means, in combination, relay means for stopping said tuning means, an electron tube having a plate circuit connected to said relay means and a grid controlling the plate current for operating said relay means to stop said tuning means, a tuned circuit in said receiver through which the signal producing the sound output of said receiver passes, means including a rectifier energized by the signal after passage through said tuned circuit adapted to apply a rectified control voltage to said grid for operating said relay means to stop said tuning means when a carrier signal is closely tuned in, and means associated with said tuned circuit and controlled by said relay means for reducing the selectivity of said tuned circuit when said tuning means is stopped.

4. In a radio receiver having variable tuning means, in combination, power means driving said tuning means, relay means operable to stop and start said power and tuning means, an electron tube having a plate circuit connected to said relay means and a grid controlling the plate current for operating said relay means to stop said tuning means, a tuned circuit in said receiver through which the signal producing the sound

output of said receiver passes, means including a rectifier energized by the signal after passage through said tuned circuit adapted to apply a rectified control voltage to said grid for operating said relay means to stop said tuning means when a carrier signal is closely tuned in, and means associated with said tuned circuit and controlled by said relay means for increasing the selectivity of said tuned circuit when said tuning means is started and decreasing the selectivity of said tuned circuit when said tuning means is stopped.

5. In a radio receiver having variable tuning means, in combination, power means driving said tuning means, relay means operable to stop and start said power and tuning means, an electron tube having a plate circuit connected to said relay means and a grid controlling the plate current for operating said relay means to stop said tuning means, a tuned circuit in said receiver through which the signal producing the sound output of said receiver passes, means including a rectifier energized by the signal after passage through said tuned circuit adapted to apply a rectified control voltage to said grid for operating said relay means to stop said tuning means when a carrier signal is closely tuned in, and means associated with said tuned circuit and controlled by said relay means for increasing the selectivity of said tuned circuit when said tuning means is started and decreasing the selectivity of said tuned circuit when said tuning means is stopped, and means actuatable by an operator for operating said relay means to restart said power and tuning means.

6. In a radio receiver as claimed in claim 4, wherein said electron tube, tuned circuit and rectifier constitute elements of a radio receiver used for the reproduction of audible signals.

7. In a radio receiver as claimed in claim 4, wherein the rectifier is the rectifier supplying an automatic volume control voltage to an amplifying tube of said receiver.

EDWARD F. ANDREWS.
